UNITED STATES PATENT OFFICE

GEORGE HOPP, OF NEW YORK, N. Y.

CANOPY

Application filed September 27, 1928. Serial No. 308,825.

The present invention relates to improvements in canopies in use, for entrances to buildings, for golf courses, for swimming pools and other suitable places where such 5 covering is necessary.

In canopies as hitherto used it has been customary to make the main frames thereof of single units of pipe or metal bar. Where large canopies are involved these frame units 10 are very very heavy and it often requires as many as five or six men to handle them, in the erection or in taking down. Furthermore up to the present time the shapes of the canopies have been limited due to the fact 15 that the frame rods when of single pieces necessarily limit the variety of shapes possible.

One of the objects of the present invention is to permit canopies to be made of any 20 shape, with straight, curved or arched legs.

A further object is to provide a construction whereby my canopy may be made up of small sections.

Another object is to provide a construction 25 which will be easy and cheap to manufacture and also be easy to erect and remove.

Still another object is to construct my canopy so that when used at golf courses, swimming pools and the like, it may be adjusted 30 to fit the conditions, such as the angle of the sun's rays, and the flatness of the ground and other details.

With these and other objects in view my device consists in the novel construction and 35 arrangement of parts hereinafter more fully described, and shown in the accompanying drawings which form part of this specification and in which similar reference characters denote corresponding parts.

40 Fig. 1 is a perspective view of the assembled frame work of one form of canopy.

Fig. 2 is a cross sectional view of a detail along line 2—2 of Fig. 1 looking in the direction of the arrows.

45 Fig. 3 is a perspective view of the same detail, and,

Fig. 4 is a perspective view of another form of canopy embodying the elements of my invention.

50 In the embodiment of my invention as

shown in Fig. 1, my canopy frame work comprises two or more supporting frames 10 of metal pipe, wood or any suitable material suitably joined together by means of cross bars 11 of similar material designed to engage in members positioned on each of the frames, and for instance comprising collars or sleeves 12 positioned on the frames 10 and having laterally projecting portions 12', in which holes are bored and into which tongues 12" projecting from the cross bars 11 are adapted to be engaged. The tongues 12" may be formed by bending over the ends of the bars 11 or by other suitable ways.

Each of the frames 10 of my canopy is comprised of two or more sections 13 and 14 of metal pipe or other suitable material and which may each have any desired curvatures. The lower ends 13' and 14' respectively of the various sections may be finished off by pointing or provided with feet or the like as desired (not shown). The upper ends 13" and 14" respectively thereof are threaded to engage in suitable screw threaded openings in a joining device 15 which comprises two L-shaped members 15' and 15" each having an opening 16 in the longitudinal section of the L for the passage therethrough of a fastening bolt 17, and being also provided with threaded openings 18 and 19 respectively in their transverse sections for engagement of the respective threaded portions of pipe sections 13 and 14.

The two L-shaped members 15' and 15" are mounted with transverse sections extending in opposite directions as shown clearly in Fig. 3.

The bolt 17 may have a plain head 17' or 90 may be provided with an enlarged portion 17" integrally formed or otherwise attached thereto and having suitably spaced openings therein, in order that the frame may be fastened to the wall of a building or the like if desired.

The nut 20 into which said bolt screws is in the present embodiment an L-shaped member having a threaded opening for engagement with the bolt in one of its extensions and being provided in its other extension 100

with a suitable opening 20' for the passage therethrough of a transversely projecting portion 12² of one of the cross bars 11. Of course the particular coupling means for the cross bars herein specified need not be employed. Instead of the means described any other suitable arrangement may be employed, such as a nut and threaded pipe arrangement.

- 10 In the erection of my canopy the frames 10 are first assembled by screwing the sections thereof into their respective L-shaped members 15' and 15² which are then joined together in the manner indicated above. 15 Then the sections 15' and 15² are set at the desired angle and fixed in this position by tightly screwing up the bolt 17. The frame which has the enlarged bolt head 17² in its joining member is properly fastened to the 20 building and then the various cross bars 11 inserted in their respective positions therein, and also in the corresponding positions on the other frames.

It is readily seen that by the provisions of 25 joining elements 15 I have secured an adjustable canopy which may be readily handled and easily assembled and permits building of canopies of any desired shape, a thing which has been hitherto impossible due to the 30 difficulty of shaping long sections of pipe to the desired curvature.

In the modification of my canopy shown in Fig. 4, I show the adaptability of my arrangement to a canopy designed for use for 35 instance at golf courses, swimming pools or other like places. In this modification the same joining device 15 is used and the only changes herein are in the shape of the sections 22 and 23 respectively. This modification 40 serves merely to illustrate the ready adaptability of my arrangement to securing of canopies of any shapes and size. The canopy covering 24 in this case and its frame the construction of which are well known in the art 45 are adapted to be tiltable to any desired angle by reason of their connection to the members 20, and by adjusting the position of said members before tightly screwing in the bolts 17, the angular positioning of the covering frame 50 may be accomplished. Similarly the fact that each of the members 22 and 23 may be adjusted angularly due to their connection to members 15' and 15² makes it possible to adjust the members to the terrain on which the canopy stands. This last feature is also true of 55 the device illustrated in Fig. 1.

It is of course obvious that my invention may readily be modified without departing from the spirit thereof, and I do not wish to 60 be limited to the details shown and described.

What I claim is:

1. In a canopy, a framework therefor, comprising supporting frames joined by cross bars, each of said frames comprising at least 65 two shaped sections, means for joining said

shaped sections together, said means including L-shaped members provided with means for engagement with cooperating means on the ends of the respective sections of said framework.

2. In a canopy, a framework therefor including supporting frames, each of said frames comprising at least two shaped sections, adjustable means for joining said shaped sections, said means including L-shaped joining members mounted with their transverse portions extending in opposite directions and provided with means for engagement with cooperating means on the ends of the respective sections of said frames.

3. In a canopy, a framework therefor, including supporting frames joined by cross bars, each of said frames comprising at least two shaped sections and adjustable means for joining said shaped sections, said means including joining members and clamping means therefor, said joining members being provided with screw threaded means for engagement with cooperating screw threaded means on the ends of said frame sections.

4. In a canopy as per claim 3, in which said joining members and clamping means respectively comprise two L-shaped members mounted on a bolt, and a cooperating nut for said bolt for clamping said members in any desired position.

5. In a canopy as per claim 3, in which the clamping means includes a nut, having an extension with an opening for the engagement of a projection from said cross bars.

6. In a canopy as per claim 3, in which the clamping means includes a bolt having means thereon for attachment to the walls of a building.

In testimony whereof I affix my signature.

GEORGE HÖPP.
